UNITED STATES PATENT OFFICE.

AUGUST SUNDBERG AND GUSTAF ERICSSON, OF STOCKHOLM, SWEDEN.

REVERSING DEVICE FOR SHAFTS.

No. 848,981.

Specification of Letters Patent.

Patented April 2, 1907.

Application filed October 10, 1906. Serial No. 338,282.

To all whom it may concern:

Be it known that we, AUGUST SUNDBERG and GUSTAF ERICSSON, of Stockholm, Sweden, and subjects of the King of Sweden, have invented certain new and useful Improvements in Reversing Devices for Shafts; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The invention relates to mechanism for operating shafting, and consists in means for driving the motor-shaft and propeller-shaft in the same direction and at the same speed, means for maintaining the propeller-shaft stationary while the motor-shaft remains in motion, and means for reversing the direction of movement of the propeller-shaft to that of the motor-shaft.

In the accompanying drawings, forming part of the specification, Figure 1 is a vertical transverse section of the device, the operating-cranks and connecting-rods being shown diagrammatically, the full lines designating the motor-shaft connections and the dotted lines designating the propeller-shaft connections; and Fig. 2 is a central horizontal section.

Referring to the drawings, *a* designates the motor-shaft, having a balance-wheel *a'* fixed on its inner end, and *b* the propeller-shaft, mounted in line of the axis of the shaft *a* and having a disk *k* fixed on its inner end.

A supporting member, such as a drum *n*, surrounds the balance-wheel and is loosely mounted on the motor-shaft *a*. This supporting member carries or supports a guide-rod *o*, which extends across the diameter thereof and having slides *l* *m*, respectively, mounted at each end. The slide *l* is connected with the shaft *a* by means of a rod *p*, pivoted to the slide and to an eccentric or crank pin *c*, fixed in the hub of said balance-wheel. The slide *m* is connected with the same shaft through a rod *s*, pivoted to the slide and to an eccentric-pin *d*, carried on a crank arm or disk *g*, rigidly secured to the crank-pin *c*. The propeller-shaft *b* is connected with slide *l* by means of a rod *r*, pivoted to the latter and to an eccentric or crank-pin *e*, fixed on the disk *k*. This crank-pin *e* has a crank-arm *h* fixed thereon, which

carries a crank-pin *f*, on which is mounted a rod *t*, pivotally connected to the slide *m*.

The drum *n* has a head *u* fixed thereon, which surrounds the disk *k* and is provided with a friction clutch-ring *B*, concentric to the propeller-shaft *b*. A friction clutch-wheel *D* is mounted to rotate with the shaft *b*, but is movable longitudinally thereon into and out of engagement with the ring *B* by any suitable means and for the purpose now to be described.

When the clutch-wheel *D* is in engagement with the ring *B*, as shown in Fig. 2, and the motor-shaft *a* is being rotated in the direction indicated by the arrow, the crank-pin *c* and crank *g* will, through their respective connectings with the slides *l* and *m*, exert pressure on the guide-rod *o*, and thereby rotate the drum *n* and its head *u*, which latter being clutched to the propeller-shaft will rotate it in the same direction and at the same speed as the motor-shaft, while the mechanism inside the drum remains stationary relatively to the drum and shafts. Assuming now that the clutch-wheel *D* is moved out of engagement with the clutch-ring *B*, the rotation of the motor-shaft will continue to rotate the drum at one-half the angular speed of the shaft; but the drum not being connected with the propeller-shaft the latter remains stationary. If now the drum be held against rotation by any suitable means, such as a band *v*, around the friction-wheel *B*, the propeller-shaft will be rotated in an opposite direction to that of the motor-shaft through the medium of the disk *k*, which is connected, as above described, with the balance-wheel *a'*. The reversal of rotation of the shafts is due to the relative positions of the pins *c* and *e*. The downward movement of pin *c* from the position shown in Fig. 1 will cause the slide *l* to move away from the axes of the shafts, and as the pin *e* is below the axes the shaft *b* will be rotated to the left.

We claim—

1. The combination with a motor-shaft and a propeller-shaft in line therewith, of reciprocating members, a crank on each shaft and means connecting both cranks with the reciprocating members.

2. The combination with a motor-shaft and a propeller-shaft in line therewith, of conjointly-reciprocating members, cranks on each shaft, and means connecting the cranks with both reciprocating members.

3. The combination with a motor-shaft and a propeller-shaft in line therewith, of a guide, slides mounted on the latter, cranks on each shaft and means connecting the cranks 5 with the guide.
4. The combination with a motor-shaft and a propeller-shaft in line therewith, of a supporting member, a guide carried by the latter, slides on the guide, a crank on each 10 shaft, and means connecting each crank with the slides.
5. The combination with a motor-shaft and a propeller-shaft, of a rotatable supporting member, a guide carried by the latter, a 15 crank on each shaft, and means connecting the cranks with the guide.
6. The combination with a motor-shaft and a propeller-shaft, of a rotatable supporting member, a guide carried by the latter, a 20 crank on each shaft, rods connected with each crank, means connecting the rods, and means to lock the supporting member to the propeller-shaft.
7. The combination with a motor-shaft 25 and a propeller-shaft, of a supporting member, a guide fixed in the latter, slides on the guide, a crank on each shaft, rods connecting the cranks with the slides, and means to connect the supporting member with the propeller-shaft.
8. The combination with a motor-shaft and a propeller-shaft, of a supporting member loosely mounted on the shafts, a guide mounted in the supporting member between 30
- the ends of the shafts, slides mounted on the 35 guide, a crank carried by each shaft, rods connecting the cranks and one of the slides, a second crank carried by each shaft connected with the other slide, a clutch-ring carried by the supporting member, and a clutch-wheel 40 on the propeller-shaft adapted to be moved into and out of engagement with the clutch-ring.
9. The combination with a motor-shaft, of a slide adapted to be reciprocated thereby, a 45 propeller-shaft, and mechanism operated by the slide to rotate the propeller-shaft in a direction opposite to the direction of rotation of the motor-shaft.
10. The combination with a motor-shaft 50 having a crank mounted thereon, of a slide, a rod connected to the crank and slide, a propeller-shaft, a crank mounted thereon, and a rod connected to the slide and to the last-named crank at a point angularly displaced 55 with relation to the point of connection of the first-named crank and rod, whereby the propeller-shaft is rotated in a direction opposite to the direction of rotation of the motor-shaft.

In testimony that we claim the foregoing as our invention we have signed our names in presence of two subscribing witnesses.

AUGUST SUNDBERG.
GUSTAF ERICSSON.
